UNITED STATES PATENT OFFICE

CHARLES ANDREWS, JR., OF ROCKFORD, ILLINOIS, ASSIGNOR TO ANDREWS WIRE & IRON WORKS, OF ROCKFORD, ILLINOIS, A CORPORATION OF ILLINOIS.

TOASTER.

No. 897,513.

Specification of Letters Patent.

Patented Sept. 1, 1908.

Application filed February 6, 1908. Serial No. 414,619.

To all whom it may concern:

Be it known that I, CHARLES ANDREWS, Jr., a citizen of the United States, residing at Rockford, in the county of Winnebago and State of Illinois, have invented certain new and useful Improvements in Toasters, of which the following is a specification.

The object of this invention is to construct a toaster in which a perforated bottom plate is at varying distances from the wire top, in order that the heat may act uniformly on the articles being toasted.

In the accompanying drawings, Figure 1 is a top view of the toaster. Fig. 2 is an under-face view. Fig. 3 is a vertical section.

The sheet metal bottom and support for the wire top is formed of a single piece, and comprises the main portion 1 formed with perforations 2, and depressed in its center. The edges of the center portion are rolled to form the supports 3 and again turned back to form the wire rests 4. The wire top 5 has its edges located within the rests 4. A handle 6 is formed of wire, and has its ends inserted through openings in the rests 4 and turned down through openings in the main portion 1, and turned back to form clenchers. This construction makes a three part toaster,

namely, the sheet metal section, the wire top and the handle, which are cheaply constructed and put together.

By forming the main portion so that it is depressed at its center, the heat being greater at the center will have farther to travel after passing through the perforations before coming in contact with the article being toasted, than the heat which is not so intense passing through the perforations near the outer edge of the toaster. By locating the perforations at varying distances from the wire top, the heat will be uniform throughout the extent of the toaster.

I claim as my invention.

A toaster comprising a perforated sheet metal main portion having its center depressed and formed with V shaped edges, the outer walls of the edges formed with rests, and a top seated in the rests in a fixed manner.

In testimony whereof I have hereunto set my hand in presence of two subscribing witnesses.

CHARLES ANDREWS, JR
